GARMENT CONSTRUCTION

Joseph Clyne, Bronx, N. Y., assignor, by mesne assignments, to Flexsleev, Inc., a corporation of New York

Application August 29, 1947, Serial No. 771,342

1. Claim. (Cl. 2—93)

1 My invention relates to improvements in garments and more particularly to an improved jacket or coat construction in which the elements are combined in such a manner as to provide a normal fit for the wearer and at the same time provide a construction which will permit free movement of the arms and body of the wearer.

This application is a continuation-in-part of my pending applications, Serial No. 595,411, filed May 23, 1945, for "Garment" and Serial No. 627,009, filed November 6, 1945, for "Garment and Garment Construction," now respectively Patents Nos. 2,426,818 and 2,426,819. The subject matter disclosed but not claimed in these applications, is claimed herein.

When a person wearing a jacket of common construction attempts to raise his arm, it is a common experience to find that the sleeve of the jacket places a strain on the upper arm muscle so that the wearer does not have free movement of his arm. Furthermore, it is a common experience to find that the wearer of an ordinary jacket cannot raise his arms without pulling the rest of his garment out of position, to either twist it around his body, or make it ride up. This is particularly true if the wearer of the garment is in a sitting position. In some cases, it is very difficult for one in a sitting position to raise his arms when wearing a jacket of ordinary construction. The strains produced on the arm muscles under such conditions necessarily make the wearer of the garment uncomfortable and gives him the feeling that his arms are held down under tension.

The primary object, therefore, of the present invention is to provide an improved garment construction which will overcome the difficulties and objections referred to above, and particularly to provide a jacket or coat having set-in sleeves in which there is a minimum of restraint against free arm movement.

Another object of the invention is to provide an improved garment construction which permits raising of the wearer's arms without strain on his arm muscles and without pulling the rest of the garment out of its normal position.

A further object of the invention is to provide an improved garment construction which is adapted to permit the free swinging of the arms.

According to one form of the invention, the improved garment construction comprises a garment having front and back sections attached to each other under the armhole by a seam, a dart

5 in the front section of the garment extending to the armhole, an integral allowance of the extra material on each side of the dart at the armhole, an under sleeve section and a top sleeve section each provided with an integral allowance, the sleeve allowances being attached to the allowances on the front section of the garment, thereby providing a garment having an armhole of substantially standard circumferential 10 measurement while the jacket permits the free swing of the sleeve with respect to the remainder of the garment.

Instead of providing a two-section sleeve, a single-piece or combined sleeve may be provided 15 in which the armpit section includes an allowance of particular configuration adapted to be attached to the body section of a garment provided with an integral allowance or allowances at the armhole, of the type described above.

20 The two-piece sleeve provided with the special shaped allowances may be front and back sleeve sections, and the sleeve in any form may be Raglan or standard.

The garment of the present invention is no 25 more difficult to make than a standard garment, and may be manufactured without additional cost to the wearer.

Other features, objects and advantages of the 30 improved jacket construction of the present invention will be apparent to those skilled in the art from the following more detailed description taken in connection with the accompanying drawings forming a part of this application.

In the drawings:

35 Fig. 1 is a view partly to one side, of one form of jacket constructed in accordance with the features of the present invention, illustrating the relationship between the sleeve and the body of the jacket with the sleeve in raised position.

40 Fig. 2 is a view showing the front and back sections of the jacket of Fig. 1, with the front section provided with a dart and with an integral allowance on each side of the dart.

45 Fig. 3 is a view of the top and under sections of a two-piece sleeve such as shown in Fig. 1, in which each section is provided with a compound allowance of particular configuration.

50 Fig. 4 is a view of a one-piece sleeve combining front and back sections, provided with a special allowance adapted to provide a portion of the armpit of the garment.

Fig. 5 is a broken side view of a garment showing the appearance of a jacket made with a one-piece sleeve as illustrated in Fig. 4.

Fig. 6 is a view similar to that of Fig. 3 rep-

resenting a top sleeve and under sleeve in which the allowance includes a substantial projection on the under sleeve section.

Fig. 7 is a view representing a combined under sleeve and top sleeve, including an integral allowance similar to the combined allowance of Fig. 6.

Fig. 8 is a diagrammatic pattern type view showing front and back sections of the waist portion of a garment of the Raglan sleeve type and which includes integral armpit allowances forming structures of special configuration.

Fig. 9 is a pattern type view showing back and front sleeve sections of the Raglan type each having armpit allowances somewhat similar to those of Fig. 3.

Fig. 10 is a view partly to one side of a garment having a waist portion constructed of the elements shown in Figs. 8 and 9, and having the general under-arm appearance of the garment shown in Fig. 5.

Referring to Fig. 1 of the drawings, this view shows a jacket constructed of suitable fabric in accordance with the present invention, from front and back body sections similar to those shown in Fig. 2 but having a standard armhole, and under and top sleeve sections patterned the same as those shown in Fig. 3. In Fig. 1 the jacket comprises a front section 10 attached to a back section 12 by means of a seam 14 which extends to the armpit. The front section 10 includes a dart 16 which also extends to the armpit. The two back sections of course are attached to each other by seams in the back of the jacket.

The sleeves of the jacket shown in Fig. 1 comprise an under sleeve section 18 of the same pattern as that shown in Fig. 3 and a top sleeve section 20 of the same pattern as that shown in Fig. 3. These sleeve sections are attached to each other by a front seam 22 and a back seam, not shown, the front seam substantially matching the position of the dart 16. The sleeve is attached to the armhole section of the front and back sections of the garment by means of a seam 24. The jacket of Fig. 1 includes the usual collar and pockets, as indicated, which may be of any desired style.

The under sleeve section 18 of the jacket, as shown in Fig. 3, differs substantially from the standard sleeve pattern at the armhole section of the sleeve, the shape of the standard sleeve pattern where it differs from the sleeve section 18 being indicated by a dotted line 26. Therefore, according to the present invention, the under sleeve section 18 includes at the armhole additional material or a compound allowance 28 integral with the sleeve section and of crescent shape, which is enlarged or wider toward the armpit section of the sleeve. This allowance includes an integral tail piece or extension 30 extending substantially along the front edge of the under sleeve section. The armhole end of the under sleeve section 18 as modified by the allowance 28 therefore includes a substantially short edge extending laterally from the edge 40, a shallow relatively long curve over the major portion of the end of the sleeve, and another short straight downwardly sloping edge extending to the sleeve edge 36. In this structure the edge 36 is nearly as long as the edge 40 so that when the arm is raised there is ample material at the armpit to give freedom of arm movement.

The top sleeve section 20 as shown in Fig. 3 also differs from the standard pattern which is indicated by the dotted line 32. This section of

the sleeve therefore includes a substantial allowance at the armpit and along the lower edge of the sleeve section which is integral with the material of the sleeve. This allowance has a double wing-shaped configuration, one wing of which, 34, extends from the front edge of the sleeve along the armpit section, while the other wing, 35, extends substantially along the front edge of the sleeve from the armpit section. The allowances 34 and 35 make the shoulder portion of the top sleeve 20 substantially symmetrical and the edges 38 and 42 substantially equal, the end edge comprising a rather gentle convex curve the center of which is attached to the shoulder of the garment.

In making up the sleeve of the jacket shown in Fig. 1 from the sleeve sections 18 and 20 shown in Fig. 3, edge 36 is attached to edge 38 by means of a seam to form the seam 22 shown in Fig. 1, while an edge 40 of the under sleeve section 18 is attached to the edge 42 of section 20 by means of a seam. When the sleeve sections 18 and 20 are sewed together, the tail or wing allowance 30 is sewed to the wing allowance 35, and the ends of the allowances 28 and 34 are also sewed together since they comprise a portion of the edges 36 and 38. The allowances 30 and 35 serve to provide a sleeve having an armpit section which is slightly larger than the standard sleeve, but the allowances 28 and 34 provide a sleeve which gives the wearer freedom to swing his arms and raise them in any position without having his arm muscles placed under any sleeve strain or tension. The illustration in Fig. 1 shows the appearance of the sleeve in raised position when the sleeve sections include the allowances shown and described in detail in connection with Fig. 3 of the drawings.

Fig. 2 of the drawings shows the structure of the back and front sections of a preferred form of jacket made in accordance with the present invention, the back section 44 corresponding to the back section 12 in Fig. 1 or the same as the standard pattern, and including only a relatively small portion of the armhole at 46. The front section 48 of the jacket has a pattern of the form shown in Fig. 2 and includes the edges 50 which form a dart which extends into the armhole portion of the jacket. The front also includes a fitting dart 52 in front of the dart edges 50, the edges of both of which are sewed together in completing the dart. The front section 48 in other respects differs substantially from the standard pattern by providing complementary under-arm allowances 54 and 56, on opposite sides of the dart 50. Each of these allowances 54 and 56 comprises a substantially triangular-shaped section extending beyond the edge of the armhole of the standard pattern, as indicated by the dotted lines 58 and 60. While the allowance 56 is shown as triangular, the allowance 54 is a four-sided irregular polygon in which the top edge is intended to match the upper sloping edge of the allowance 56 when the edges 50 are sewed together, thereby providing an armhole contour of two curves which meet in a peak in the lower portion of the armhole.

In making a jacket having front and back sections as shown in Fig. 2, and sleeve sections as shown in Fig. 3, the sleeve sections may be joined in the manner described above, while the back and front sections 44 and 48 are attached to each other by sewing together the adjacent edges 62 and 64. The edges 50 are sewed together and the fitting dart 52 is also sewed up, while any buttonholes or

buttons or other fastening means are provided on the front section 48 adjacent the edge 66. It will be understood that for each jacket two front and two back sections are provided and that the two back sections will be joined by sewing together two edges 68. After the sleeve shown in Fig. 3 has been assembled as described above, it is sewed into the armhole after the top shoulder seam of the jacket body is made, in the usual manner. A jacket made from material cut in the manner shown in Figs. 2 and 3 has the general appearance of the jacket shown in Fig. 5 in which the effect of the under-arm allowances 54 and 56 in raising the material under the arm is readily apparent.

By combining the allowances 28, 30, 34 and 35 with the allowances 54 and 56, a combined sleeve and body structure is provided which gives unusual freedom for the movement of the wearer's arms. The arm may be raised freely without pulling the body and jacket up and without binding the arm muscles, and particularly the upper arm and shoulder muscles used in raising the arms. Furthermore, the adjacent body and arm construction provides a jacket having a very neat appearance. There is no bagginess or apparent extra fullness which would detract from the style and appearance of the jacket. The sizes of the armhole structure is not materially enlarged over that of a jacket made from a standard pattern, so that this feature, taken in conjunction with a combination of the particular shaped allowances, provide a very effective and practical jacket construction.

Fig. 4 shows a single-piece sleeve 70, combining front and back sleeves, which may be employed in place of the two-piece sleeve construction shown in Fig. 3, in making a jacket either of the form shown in Fig. 1 or of the form shown in Fig. 5. A preferred construction for using the single-piece sleeve 70 is the combination of this sleeve with the body sections 44 and 48 as shown in Fig. 2. This combination produces a jacket having substantially the appearance of the jacket shown in Fig. 5.

The single-piece sleeve 70 differs from a standard single-piece sleeve pattern by the complex under-arm allowance 71, between the dotted line 72, representing the shape of the standard sleeve pattern where it differs from the sleeve 70, and the line 74 representing the upper edge of the allowance 71. The complex armpit allowance 71 between these lines is generally the shape of a crescent with a scalloped lower edge so that the line 72 is of substantially different shape from the line 74. The latter line forms a gentle symmetrical curve of low or relatively small amplitude between the opposite peaks forming the top shoulder part of the sleeve.

In making up a jacket with the sleeve 70, the body sections 44 and 48 are combined as described above, while the top edges 76 and 78 of the sleeve 70 are sewed together to complete the sleeve, which is then set in the armhole provided by the sewing up of the back and front sections 44 and 48. In the finished jacket, the allowance 71 is combined directly with the gores 54 and 56 to provide a jacket construction having a form very similar to that shown in Fig. 5. The sleeve 70 is set in the armhole with the gores 54 and 56 pointing directly into approximately the center of the allowance 71 or of line 74. The seam formed by joining the edges 76 and 78 will be substantially at the upper back portion of the sleeve.

The single-piece sleeve 70 may also be used in a jacket body of a standard pattern such as shown in Fig. 1. However, the sleeve will differ from that shown in Fig. 1 because it will not include the gores 30 and 35 of Fig. 3 and will not include the seam 22. While the cuff portion of the sleeve shown in Fig. 3 differs from that in Fig. 4, this is a matter of style, not comprising a feature of the present invention.

10 The sleeve construction shown in Fig. 6 includes an under sleeve 80 and a sleeve or top sleeve 82 which differs from the sleeve construction shown in Fig. 3 by including a projection 84 on the allowance of the under sleeve. In this figure, as in Fig. 3, the dotted lines represent the extent of the standard patterns. The under sleeve 80 therefore has a special shape because of the projection 84, including two similar curves, one of which runs to the front seam and the other 20 of which extends up to a straight edge near the opposite edge of the sleeve. This sleeve construction may be combined with standard body units to make a garment of the style shown in Fig. 1 of the drawings.

25 Fig. 7 shows a sleeve 102 comprising a combination of an under and top sleeve similar to those shown in Fig. 6, in which the dotted line represents the outline of the standard sleeve pattern where it differs from that of the sleeve 102. This 30 sleeve 102 may be combined with the body elements 44 and 48 shown in Fig. 2, or with standard body elements to produce a style similar to that shown in Figs. 5 and 1, respectively. The sleeve 102 includes a substantially symmetrical generally crescent-shaped armpit allowance 104 having an enlarged central body section and side sections which terminate substantially at a point. This gives a low wave curve for the armpit edge in place of the usual deep valley, to provide a 40 gentle slope into the large shoulder curve. The use of this sleeve provides a garment in which there is only one seam in the sleeve, at the back, and in which the allowance gives ample freedom for lifting the arm.

45 Figs. 8, 9 and 10 illustrate a modification of the garment construction of the present invention in which the sleeve of the garment integrally includes a shoulder section to provide a garment of the Raglan type. In Fig. 8 a front waist section 118 includes an armpit allowance 120 represented by the area enclosed by the full line edges and the dotted line. The waist portion of the garment also includes a back section 122 having an integral armpit allowance 124 bordered by the 55 full line edges and the dotted line, as shown. Instead of the sleeve-attachment lines being straight for the sections 118 and 122, they extend nearly to the side edges and then turn upward abruptly. At the same time, the adjacent edges extend up farther than usual to substantially meet the upwardly-turned curves bordering the upper portion of the allowances 120 and 124.

The sleeve of the modified garment shown in 65 Fig. 10 includes a back sleeve 126 and a front sleeve 128 as shown in Fig. 9. These sleeves are somewhat similar to those of Fig. 3 in that they include the allowances 130 and 132 respectively, having substantially the same wing shape or 70 tapering portions. However, these sleeve sections 126 and 128 have a regular convex smoothly curved edge at the top where the sleeves are joined to the body portions of the garment and do not have the abrupt slope of the standard 75 Raglan sleeve. As a result of the allowances 130

and 132, the adjacent edges of the sleeve sections more nearly approach the length of the remote edges and provide almost interchangeable sleeve sections.

When the elements of the garment shown in Figs. 8 and 9 are assembled and sewed together, they provide a garment waist section having the style and function shown in Fig. 10 in which the allowances 120 and 124 in combination with allowances 130 and 132 and their contours effect an upswing of the seams attaching the sleeves at the armpit of the garment. This gives a bow curve effect similar to that shown in Fig. 5, the construction being such that freedom of arm movement is provided for in combination with a garment structure in which the sleeves integrally include the shoulder of the garment.

My improved garment construction illustrated in Figs. 8, 9 and 10 comprises a combination particularly advantageous in connection with Raglan and similar type sleeves, to provide a garment which gives freedom of movement of the wearer's arms without binding the arm muscles and without distorting the garment on the body of the wearer. The provision of the underarm allowances of the particular structures described above appears to offset the normal binding character of the particular types of sleeves referred to. It is therefore possible, according to my invention to provide garments having sleeves of various type and at the same time have a garment in which the wearer has unusual freedom of arm movement.

While it will be apparent to those skilled in the art that various types of garments may be made in accordance with the different forms of the invention, it may be pointed out that the form shown in Figs. 1 to 3 is particularly adapted for use in connection with men's and ladies' jackets and the same is true for the modifications shown in Figs. 6 and 7. The form of garment shown in Figs. 4 and 5 are advantageously employed in connection with the making of coats for various purposes. The Raglan type of garment illustrated in Figs. 8, 9 and 10 is advantageously employed for the making of men's and ladies' coats for various purposes. It is to be further understood of course that the improved garment construction may be employed in various types of apparel including ladies' waists, men's shirts and other apparel.

The improved garment construction of the present invention results from a combination of relatively simple structural features which give the garment a sleeve and armpit structure permitting free movement of the wearer's arms without distorting the garment and without binding the arm muscles. A wearer of the garment of the present invention may raise his arms in any

position without breaking the sleeve or pulling the body of the garment out of its normal position. From the foregoing description, it will be apparent that certain variations may be made in the structure of the garment and still achieve the objects of the invention. Such changes are contemplated as coming within the spirit and scope of the invention.

What I claim as new is:

- 10 In a sleeved garment, an improved waist construction providing for freedom of arm movement of the wearer of the garment, comprising a garment waist portion including a front section and a back section joined together by a seam 15 at the side of the garment below the sleeve, a sleeve for the garment including a substantial integral armpit allowance blended into the attachment end of the sleeve to provide an attachment edge having curves of relatively small amplitude, said sleeve armpit allowance including a portion extending along the front portion of the attachment edge of the sleeve and gradually diminishing in width toward the top of the attachment edge of the sleeve thereby providing a gentle slope along the front portion of and toward the top of the attachment edge of the sleeve, the front section of the waist including an armpit attachment edge to which the armpit attachment edge of the sleeve is attached, a dart 20 extending through said armpit attachment edge of the front section of the waist, an upwardly projecting complementary allowance at each side of the dart in the armpit portion of the front section of the waist where the sleeve is attached, 25 and seams joining said sleeve to the front and back sections of the garment so that the sleeve allowance is joined to the waist allowance, whereby a garment is provided which permits free arm movement of the wearer and which also permits the wearer to readily raise his arms without distorting the position of the garment on the body of the wearer and without binding the wearer's arm muscles.
